[57] CLAIM

The design of a portable telephone talking calculator, as shown and described herein.

DESCRIPTION

FIG. 1 is a front elevational view of the portable telephone talking calculator showing my new design;
FIG. 2 is a top plan view thereof;
FIG. 3 is a bottom plan view thereof;
FIG. 4 is a left side elevational view thereof, the right side elevational view being a mirror image thereof; and,
FIG. 5 is a rear elevational view thereof.

*Fig. 2**Fig. 1**Fig. 3*

*Fig. 5**Fig. 4*
